UNITED STATES PATENT OFFICE.

THOMAS MARR AND CHARLES W. SMITH, OF WARRENTON, VIRGINIA.

DRILL-TOOTH.

SPECIFICATION forming part of Letters Patent No. 447,518, dated March 3, 1891.

Application filed July 7, 1890. Serial No. 357,936. (No model.)

To all whom it may concern:

Be it known that we, THOMAS MARR and CHARLES W. SMITH, citizens of the United States, and both residing at Warrenton, in 5 the county of Fauquier and State of Virginia, have invented certain new and useful Improvements in Drill-Teeth, of which the following is a specification.

Our invention relates to that class of drill-teeth which are provided with removable points; and the object of our invention is to make the points of an improved form and to attach them to the boots of the drill in an improved way.

15 The subject-matter claimed is hereinafter designated.

In the accompanying drawings, Figure 1 is a perspective view of a seed-drill with our improvements applied. Fig. 2 is a vertical 20 central section, and Fig. 3 is a transverse section.

The drill-boot A is of any approved construction. Our invention does not involve any change in the boot itself, as we contemplate 25 plate so forming the point that it may be readily adapted and attached to any usual form of boot. The point B is curved in cross-section, adapted to fit closely the front of the boot. The opposite ends are curved out- 30 wardly and the main body portion is nearly straight or only slightly curved.

The longitudinal edges of the point or tooth are made thinner than the central portion, and are annealed, so as to be readily bent or 35 shaped to fit any boot. The central portion and the opposite ends are tempered to afford the requisite strength and rigidity. In the central portion we form a series of holes b, four being shown in the drawings, and the 40 outer edges of these holes are countersunk to receive the head of the bolt C, so that the outer face of the head of the bolt lies flush with the surface of the tooth, so that there is no liability to catch dirt, &c., which would 45 obstruct the tooth and hinder its easy work-

ing. Only one hole a is made in the boot, and through this hole the bolt C extends. The nut D is made of a sufficient size to enable a wrench to be easily applied, and the inner face of the nut is rounded to fit snugly 50 the inner curved surface of the boot. The nut is of a depth corresponding with the length of the bolt between its inner end and the inner face of the boot. By this arrangement the tooth or point is rigidly secured to 55 the boot. There is no danger of slipping, and all auxiliary appliances for preventing the point from slipping are dispensed with.

By means of the holes b the point may be set to any desired position to accommodate wear, 60 and may be reversed. As before stated, the under side of the point fits closely the front face of the boot, and there is no "giving," rocking motion, or undue strain on the connection between the point and the boot. 65

We claim as of our own invention—

1. The herein-described point or tooth for seed-drills, having bent pointed opposite ends and annealed longitudinal edges, which are thinner than the tempered body and ends of 70 the tooth, the body of the tooth being provided with one or more apertures, for the purpose specified.

2. The combination, substantially as hereinbefore set forth, of the boot, the tooth or 75 point having bent pointed opposite ends and a series of countersunk holes on its outer face, a headed bolt extending through one of the holes and through a hole in the boot and having its head countersunk in the hole, and 80 a nut having a rounded inner face resting against the inner surface of the boot.

In testimony whereof we have hereunto subscribed our names.

THOMAS MARR.
CHARLES W. SMITH.
